UNITED STATES PATENT OFFICE.

DAVID WILLIAM HUDSON, OF GREEN BAY, WISCONSIN.

NAPKIN AND THE LIKE.

Application filed April 6, 1925. Serial No. 21,008.

This invention relates to improvements in napkins and the like. More particularly stated, this invention relates to improvements in paper napkins and packages thereof, and the invention resides particularly in the peculiar manner in which the napkins are folded.

There are many kinds of napkin dispensers on the market. One type of dispenser comprises a case of some sort with an opening through which the napkins may be withdrawn. Another type of dispenser comprises a series of upright posts between which the napkins are confined in a pile so that the top napkin of the pile may be withdrawn. In many lunch rooms dispensers are not used at all and the folded napkins are simply placed in a tumbler or large drinking glass from which the customers may withdraw their own napkins. Where dispensers are used it is usually for the purpose of keeping the napkins clean and making it possible and likely that the user will touch or come in contact with only the single napkin which he is withdrawing for his own purposes. Many such containers have a very limited capacity and are filled frequently by the introduction of comparatively small portions of the original napkin package.

Foremost among the objects of the present invention is the provision of a napkin so folded as to lend itself readily to use in any of the three dispensing methods outlined above. In other words, it is my purpose to provide a napkin so folded as to fit within a container or dispenser in a position to be readily grasped by the user; to fit readily within a container of the type having upright posts; and to be receivable with either end uppermost in a drinking glass or tumbler.

It is my further object to provide a napkin which is so folded as to provide a portion readily subject to grasp by the user and so disposed with reference to the body of the napkin that the top napkin in a dispenser may be withdrawn without touching and without any likelihood of touching other napkins in the device.

It is my further object to package napkins having the aforesaid characteristics in such a manner that the entire package or container is receivable in the dispenser and

may be allowed to remain therein pending the withdrawal of its contents.

In the drawings:

Figure 1 is a perspective view of a napkin package embodying this invention and operatively mounted in a dispenser of the cabinet or case type, portions of the container and dispenser being broken away to expose the napkins therein.

Figure 2 is a perspective view of an open package of napkins embodying this invention operatively mounted in the four-post type of dispenser.

Figure 3 is a diagrammatic view in plan of the well known quarter folded napkin, in which further folds are made to produce the napkin of this invention.

Figure 4 shows the napkin after a further fold has been made therein to reduce it to triangular form.

Figure 5 shows in plan the completed napkin embodying this invention.

Figure 6 is a diagrammatic view taken in section on the line indicated at 6-6 of Figure 5.

Figure 7 is a diagrammatic view similar to Figure 6, showing a slightly modified fold embodying this invention.

Like parts are identified by the same reference characters throughout the several views.

In Figure 3 I have illustrated the well known quarter folded napkin, which is made by taking a square napkin and folding it in two directions on the median lines parallel to its sides. For convenience two opposite corners of this napkin will be designated with reference characters 10 and 11.

The quarter folded napkin is folded on its diagonal 12 to bring into superposed relation the corners 10 and 11. The napkin as it appears at this stage of the folding operation is shown in Figure 4. To complete the napkin of this invention a further fold is made at 13 along a line substantially midway between the apex represented by corners 10 and 11 of the napkin and the base line represented by fold line 12 thereof. The fold line 13 is preferably exactly parallel to the base of the isosceles triangle into which the napkin was folded by the first operation above described. The extent to which the apex of the triangle is made to overlap the lower portion thereof is immaterial, but in

order to make the napkin as compact as possible and to elongate as far as possible the parallelism of sides 12 and 13, the apex of the triangle is preferably folded just to the base line, as is shown in Figure 5, leaving the napkin in the form of a trapezium, the ends of which are at like angles to the base. By the word trapezium, I mean a quadrilateral having two of its sides parallel.

It is possible to get the same or a similar outline in the completed napkin by folding the corners or flaps 10 and 11 in opposite directions upon parallel and substantially superposed lines 13 and 13'. In other words, the corner or flap 10 is folded in precisely the manner in which it appears in Figures 5 and 6, and the only difference between the two folds consists in the fact that corner 11 is shown in Figure 7 to be folded in an opposite direction upon a line 13' corresponding to the fold line 13 of flap 10. The Figure 7 construction has the advantage that inasmuch as its flap portions 10 and 11 are on opposite sides of the folded napkin the napkin may be grasped readily regardless of which side is uppermost. This, however, is obviously a matter of comparatively minor convenience, since the napkins are packaged with corresponding sides uppermost, and it is a comparatively easy matter so to place a package of napkins of the Figure 5 variety in a receptacle in such a manner that the superposed flaps 10 and 11 are exposed. A further difference between the two folds arises from the fact that in the Figure 5 construction both corners 10 and 11 are grasped simultaneously, and consequently the napkin must be withdrawn from the container in a folded condition, the fold at 12 being kept from opening by the fact that the corners are both grasped by the person withdrawing the napkin. In the Figure 7 construction it will be obvious that the napkin is free to open up during its withdrawal from the container.

The napkins shown in Figures 1 and 2 may be taken to be folded either in accordance with Figures 5 and 6 or with Figure 7, since but one flap is visible at all events in the folded napkin.

In Figure 1 the dispenser comprises a base 15 upon which the body 16 is supported. The body 16 comprises side walls 17, a rear wall 18 and front wall portions 19, the latter terminating in substantially vertical margins at 20 to provide a central dispensing opening at the front of the device. The dispenser is preferably open at its top and is of a size to receive bodily a carton or container 25 holding a package of napkins constructed with lines of perforations at 26 and 27 spaced apart at substantially the distance of margins 20 of the dispenser. Thereby the entire central front portion 28 of the

container or carton may readily be turned away as shown in Figure 1 to expose the napkins, each of which lies within the container in such a manner that its folded upper flap portion is exposed through the aligned openings of the container and dispenser. The flap portion of the napkin is so readily grasped that the user will seize the napkin at this point instead of taking it by the folded margin 13. Thus, the remaining napkins in the package are protected from the contact which would result if the margins of the napkin were grasped.

The dispenser shown in Figure 2 comprises a base 30 from which four posts 31 extend vertically in a manner to define the corners of an imaginary rectangular prism. The napkin is peculiarly adapted for use with this type of dispenser for the reason that the relatively sharp acute angles formed by the convergence of its side margins 32 with the fold line 12 are well adapted to be received between posts such as those illustrated at 31 and to be confined thereby against any lateral displacement. It will be obvious that with the napkins disposed on this type of dispenser the exposed flap of the napkin is in a position to be grasped readily by the user to withdraw a single napkin from the top of the stack or package.

Furthermore, as above explained, the napkin is particularly adapted to be received within a tumbler to be dispensed in the manner commonly in use in lunch rooms. The only reason for folding the apex of the triangle shown in Figure 4 to the center line of the base portion of such triangle and thereby making fold lines 12 and 13 parallel, lies in the desirability of making a napkin which will be receivable with either end uppermost into a tumbler. At present it is customary to fold the napkins to a cornucopia shape when they are to be dispensed from a tumbler. This shape, however, is relatively difficult to package economically because it does not lend itself to the use of parallel sided containers or cartons. In the present device the fold lines 12 and 13 are sufficiently close together and the width of the completed napkin is consequently so reduced as to make the napkin receivable within a tumbler. The parallel fold lines or side margins 12 and 13 of the completed napkin not only facilitate the packaging of the napkin but also result in making it possible to insert the napkin into the tumbler with either end uppermost.

It will be seen from the foregoing description of napkins embodying this invention that the objects aforesaid are fully satisfied and that a napkin has been produced which can not only be packaged readily but which lends itself to each of the three principal known methods of dispensing napkins, and at the same time has a portion pre-

sented to the user in a manner to be readily grasped and thereby to facilitate the withdrawal of the napkin.

I claim:

- 5 1. As a new article of manufacture, a quarter folded napkin folded on its diagonal to triangular form and having the respective layers of its apex folded outwardly in opposite directions and comprising exposed 10 triangular flaps with their respective apices projecting toward the fold on said diagonal, with the reverse fold of said flaps being adapted so to reduce the transverse diameters of the folded napkin as to make it 15 receivable in a tumbler or other dispenser while providing readily accessible means for grasping the napkin from either side, whereby said napkin is adapted for use in con-

nexion with a wide variety of dispensing practices and means.

2. As a new article of manufacture, a folded napkin of trapezium form comprising a quarter folded napkin folded on its diagonal to triangular form and having the respective layers of its apex reversely folded 25 upon corresponding lines substantially parallel to the fold on said diagonal, said reversely folded layers comprising triangular flaps exposed on opposite sides of the napkin and projecting in the direction of said fold 30 on the diagonal, whereby to serve as means available from any point for grasping and opening such a napkin without disturbing other napkins which might be associated therewith.

DAVID WILLIAM HUDSON.
